UNITED STATES PATENT OFFICE

2,375,131

AUTOMATIC GAS CUTOFF

Charles C. Phillips, Cleveland, Ohio

Application July 20, 1942, Serial No. 451,557

4 Claims. (Cl. 137—15.3)

This invention relates to the art of automatic cut-off devices for valves in gas-supply lines, in connection with any gas appliance.

As is well known, there is always danger of the flame of any gas appliance being extinguished by reduction of pressure in the gas supply line. There is also the consequent danger of the gas continuing to flow in reduced pressure to and through the burner of the appliance without being burned; and there is the further aggravated danger of the gas escaping unburned from the burner when the pressure has returned to normal. Not only is there the waste of gas under such conditions but there is also the very serious danger of an explosion, as of course will be understood.

There have been attempts to remedy this situation by providing means for automatically shutting off the gas when the gas pressure falls below the predetermined point that corresponds to that of combustion at the burner, and for preventing the flow of gas to the burner from being resumed, at normal pressure, until the cut-off device is released. Instances of such devices are found in the patents to Walters No. 1,963,452, June 19, 1934, and Chandler No. 2,072,868, March 9, 1937. It is upon these patented devices that I have produced an improvement in several respects.

One object of my invention, for instance, is to provide such a device in which there is means for guiding and steadyng the valve so that the means for locking the same may be simplified; and, furthermore, it is an object to provide such means for guiding and steadyng the valve, of a comparatively simple nature.

Another object consists in providing such a cut-off device with means for preventing foreign matter from entering the same and consequently from interfering with the effective seating of the valve.

Another object is to provide such a device with a stop means, of an improved form, for limiting the extent of the valve-opening movement.

Another object is to embody in such a device, as a unitary part thereof, a pressure regulator valve for the supply of gas as it enters the device.

Another object is to provide an improved means for securing the diaphragm in assembly.

Another object is to provide such a device that can be employed with not only the familiar inflammable gas but with any form of gas including air.

In general, my object is to devise a simpler, less expensive and yet more efficient and dependable cut-off device than has been known heretofore.

Other objects will appear from the following description and claims when considered together with the accompanying drawing.

Fig. 1 is a vertical sectional view of my im-

proved device with the valve locked in closed position;

Fig. 2 is a partial view thereof with the valve in open position;

5 Fig. 2a is an enlarged view of a part of Fig. 2.

Fig. 3 is a plan view of the pressure regulator valve;

Fig. 4 is a side elevation of the pressure regulator valve;

10 Fig. 5 is an end elevation of the same;

Fig. 6 is a partial plan view of the diaphragm-securing means; and

Fig. 7 is an extended vertical sectional view thereof.

15 It is to be understood that the present form of disclosure is merely for the purpose of illustration and that there might be devised various modifications thereof without departing from the spirit of my invention as herein set forth and claimed.

20 The body of my present form of device comprises four parts, namely the bottom part 1, the diaphragm ring 2, which may be bolted to the bottom part 1, the part 3 which has screw-threaded engagement with the ring 2, and the top part 4 which has screw-threaded engagement with the part 3.

25 The bottom part 1 has the gas inlet 5 and the gas outlet 6, both of which have means of threaded engagement for the attachment of this device in the assembly intended. The inner wall 1a has an opening therethrough formed with a seat for the valve 7 which is adapted for closing the same; and the valve 7 has an upwardly and downwardly extending stem slidably and freely

30 engaging in suitable openings through the top and bottom parts of the casing for the purpose of guiding and steadyng the valve in its movement in a vertical, straight-line path. The gas, after passing the valve 7, flows through the outlet 6

35 which is in line with the inlet 5, thereby affording a substantially direct flow of gas through the device.

40 The valve 7 has connected to the upper end thereof the flexible circular diaphragm 9 of leather or other suitable material, this diaphragm having its edge portion attached to the annular ring 2 prior to assembly of the ring with the other parts. The inner flange of ring 2 has an annular recess 2a to receive the down-turned edge portion

45 of the diaphragm 9 which is secured therein by means of a ring 2b of suitable material. Then, upon screwing the part 3 into position, its lower edge will firmly clamp the ring 2b and the edge portion of the diaphragm so as to secure the diaphragm in permanent and fixed position. The ring 2b may be of a sufficiently ductile nature to respond to the compression of the part 3 and thereby serve to anchor the edge portion of the diaphragm within the recess 2a.

50 The diaphragm 9 is attached to the valve 7 in

any suitable manner, as for instance by means of a pair of washers, one of which bears against the valve, and a nut on the threaded upward extension 10 of the valve. The threaded member 11 is mounted upon the threaded portion 10 and has pivotally mounted thereupon the weighted locking member 12 which has a projection formed with a curved portion 12a adapted for locking engagement beneath the edge of the opening in the transverse wall 14. That is, the weight of the lower part of member 12 will normally turn the same, by force of gravity, about its pivot point in a clockwise direction so as to bring the curved portion 12a beneath the edge of the opening 13, this locked position of the member 12 corresponding to closed position of the valve 1, as indicated in Fig. 1. When the member 12 occupies such locked position, the valve 1 can not be opened by gas pressure but it is necessary to manually release the locking member 12 in order to open the valve. The threaded member 11 will be set at the proper position upon the threaded extension 10 at the time of assembly of the parts in order for the locking member 12 to bear proper relation to the edge of the opening 13 and thus function in the manner intended, according to a certain predetermined minimum gas pressure. Then, having once set the member 11, it will remain in such position. If so desired, there may be provided a means for locking the member 11 in such set position, as for instance a set screw.

The locking projection is so formed with the curved portion 12a that, upon turning the same counter-clockwise about its pivot point, it will clear the edge of the opening 13 so as to enter the same and permit the valve to be raised to open position, as indicated in Fig. 2. Access to the parts for this purpose may be had upon ready removal of the cover or top part 4. Then, when the locking projection has been so raised to position within opening 13 and the valve opened, as indicated in Fig. 2, the locking projection will rest against the edge of the opening 13. So long as the gas pressure remains above the predetermined minimum, as above mentioned, the locking member 12 in such position will remain idle and the valve will continue to be held open by the pressure of the gas upon the under-side of the diaphragm 9.

The extent to which the valve 1 may be opened is determined by the stop pin 15 which has screw-threaded engagement in the top part 4 so as to be readily accessible for adjustment. This pin is in alignment with the reduced stem portion 16 that projects upwardly from the extension 10 and, by means of the flush or counter-sunk head of this pin, it may be manipulated in an easy manner whenever desired, the head being provided with a screw-driver slot.

The portion 16 has free slidable engagement at all times in the flared guide extension 17 upon the under-side of the top part 4; and this arrangement serves not only in connection with stop pin 15 but also as a further means of holding the valve in vertical position and ensuring straight-line movement of the same during opening and closing. The removable stop 15 also permits ready access to the upper guide means for servicing the same so as to preclude the danger of sticking.

In order to permit the escape of any gas that might leak into the upper part of the device, I have provided the vent 18.

In the inlet opening 5 I have inserted a readily

removable filter cartridge 19 with a plurality of wire mesh screens 20 and 21 of different gauge, for the purpose of preventing the entrance of foreign particles that might otherwise adhere to the valve 1 or its valve seat and thus interfere with the proper closing of the valve. This cartridge can be removed by means of a handle 19a of wire or any other suitable form. Upon removal of the cartridge 19, it can be cleaned and replaced or a new cartridge may be inserted. These screens may be secured in position in any suitable manner. By means of having the screens 20 and 21 inclined in the manner indicated, any foreign matter will be apt to drop therefrom and hence they will not require attention as soon as otherwise.

By means of the removable plug 22 in the bottom of the device, access may be had to the lower end of the valve stem portion 8 for the purpose of supplying a suitable lubricant to prevent sticking of the same at any time. The valve stem portion 8 will always occupy position within its guide even when the valve occupies fully opened position; and the same thing is true of the valve stem portion 16 in its guide 17.

The slide valve 23 is adapted to regulate the gas pressure from the main supply line through the opening 24 in the wall 2a and is readily accessible for adjustment by means of the screw-threaded stem that extends through the wall of the bottom part 1 of the casing.

When this device is first installed, the regulator valve 23 will be set; likewise the stop pin 15 and the member 11; and the valve 1 will be opened by raising the locking member 12 in the manner above explained. It is to be understood that this device can be installed at any point in a gas-supply line, wherever it is necessary or expedient to shut off the supply of gas immediately upon reduction in pressure below a certain point. With this device, not only will the supply of gas be automatically shut off under such condition, but the valve 1 will be automatically locked closed so as to prevent any flow of gas therethrough until it is manually released. The danger of resumed gas flow to the burner, after accidental extinguishment of the burner flame, and the flow of gas through the burner and into the room occupied by the appliance, is so obvious as to require no explanation.

The regulator valve 23 will determine the gas pressure upon the lower side of the diaphragm, while the stop 15 will determine the maximum extent to which the valve 1 may be opened and thus also serve as a pressure regulator device. As is well known, a pressure regulator valve is always provided in the gas supply line; and there is a decided advantage in having the valve 23 embodied in and as part of the same device with the stop means 15. In this way, there is some reasonable assurance that these two regulator devices will both receive attention and will be set in proper accordance with each other. Furthermore, by having the pressure regulator 23 embodied in this device, the gas pressure in the supply line can be set for each individual appliance with which this automatic cut-off device is associated; and, as a result, there is no danger of the diaphragm 9 being subjected to excess pressure at any time. Thus, with my device, the gas pressure may be kept under complete control and there is every assurance of obtaining and maintaining the highest possible degree of efficiency. Also, the regulator valve 23 and its means of adjustment, in the present com-

bination, is not subjected to the usual foreign particles which are here removed by the filter.

By providing the double guide means for the valve stem, at top and bottom, there is not only ensured dependable straight-line movement of the valve without requiring any other means for this purpose, but it becomes possible also to employ a rather simple form of structure with respect to the mounting and operation of the valve-locking mechanism, as above explained.

Another advantage resides in the stop means 15 which is readily accessible at all times from the outside of the device and which does not protrude from the wall of the casing.

Recognizing the fact that there are here provided virtually two gas pressure regulating means, as above explained, both of them are readily accessible and they can be very conveniently and advantageously set the one with respect to the other, as above pointed out.

Also, there is precluded any danger of foreign particles being deposited upon either the valve 7 or its seat or upon the valve mechanism 23.

This device can be employed in connection with either natural or artificial gas, so far as the familiar inflammable gas is concerned.

Another advantage resides in the means for securing the diaphragm in assembly, with resulting convenience and efficiency. This particular means, in combination with my means for preventing undue gas pressure upon the diaphragm, will permit the diaphragm to be made of certain material which otherwise would be prohibited, and this arrangement greatly facilitates the assembly of the diaphragm when made of such material, as will be understood by those who are familiar with the art to which this invention relates.

The pressure regulator valve 23 may serve also as a means of entirely shutting off the gas supply to this device by simply setting the valve 23 in fully closed position.

While the above description refers to the use of the familiar inflammable gas, yet in the following claims the term "gas" is employed in its broader sense so as to include air or any other form of gas; and thus the scope of the following claims is not to be understood as being limited to devices for inflammable gas but is sufficiently broad to comprehend also devices for other gases including air.

What I claim is:

1. A gas cut-off device comprising a casing provided with inlet and outlet openings, a flexible diaphragm disposed substantially horizontally in said casing, a substantially vertically disposed valve for closing off the passage of gas between said inlet and outlet openings, said valve being connected to said diaphragm, said valve having a downwardly projecting stem portion and an upwardly projecting stem portion, said casing having guide means for at least one of said valve stem portions so as to ensure straight-line movement of said valve, a single locking member pivotally mounted upon said upwardly projecting stem portion, said locking member having a weighted portion below its point of pivotal mounting and having an upward projection for manipulation thereof and having an intermediate locking projection, a transversely disposed wall within said casing and having a central aperture for said locking member, said parts being so constructed and arranged that

said locking projection may be turned upwardly into said aperture, upon opening said valve, and will remain in raised position so long as the gas pressure upon said diaphragm remains above 5 a predetermined point and will be automatically lowered so as to have locking engagement below the edge of said opening in the event the gas pressure upon said diaphragm falls below a predetermined point.

10 2. A gas cut-off device comprising a casing provided with inlet and outlet openings, a flexible diaphragm disposed substantially horizontally in said casing, a substantially vertically disposed valve for closing the passage of gas between said inlet and outlet openings, said valve being connected to said diaphragm, said valve having upwardly and downwardly projecting stem portions, said casing having guide means above and below said diaphragm for said 15 valve stem portions so as to ensure straight-line movement of said valve, a single locking member mounted upon said upwardly projecting stem portion for adjustable movement therealong and for pivotal movement about a horizontal axis, 20 and means provided upon the interior of said casing for co-operative engagement by said locking member so as to automatically lock said valve in closed position in the event of the lowering of the gas pressure upon said diaphragm below a predetermined point.

3. A gas cut-off device comprising a casing provided with inlet and outlet openings, a flexible diaphragm disposed substantially horizontally in said casing, a substantially vertically disposed valve for closing the passage between said inlet and outlet openings and being connected to said diaphragm, said valve having an upwardly and downwardly projecting stem, the top and bottom parts of said casing having guide means 35 for said valve stem so as to ensure straight-line movement of said valve, locking means pivotally mounted upon the upper part of said stem, and means provided upon the interior of said casing for co-operative engagement with said locking means so as to automatically lock said valve in closed position in the event of a lowering of the gas pressure upon said diaphragm below a predetermined point.

4. A gas cut-off device comprising a casing provided with inlet and outlet openings, a flexible diaphragm disposed substantially horizontally in said casing, a substantially vertically disposed valve for closing the passage between said inlet and outlet openings and being connected to said diaphragm, said valve having an upwardly and downwardly projecting stem, the top and bottom parts of said casing above and below said diaphragm having guide means for said valve stem so as to ensure straight-line movement of said valve, the top and bottom of said casing each having an opening and a removable closure therefor permitting access to said guide means for servicing the same, locking means pivotally mounted upon said upper part of said valve stem and enclosed within said casing, and means provided upon the interior of said casing for co-operative engagement by said locking means so as to automatically lock said valve in closed position in the event of the lowering of the gas pressure upon said diaphragm below a predetermined point.

CHARLES C. PHILLIPS.
